I claim the ornamental design for a neon sign with clock, as shown and described.

DESCRIPTION

FIG. 1 is a perspective view of the neon sign with clock in a horizontal orientation, showing my new design;

FIG. 2 is a top view thereof;

FIG. 3 is left side view thereof;

FIG. 4 is a front view thereof;

FIG. 5 is a rear view thereof;

FIG. 6 is a right side view thereof;

FIG. 7 is a bottom view thereof;

FIG. 8 is a perspective view of an alternate embodiment of

the neon sign with clock in a vertical orientation;

FIG. 9 is a top view thereof;

FIG. 10 is a front view thereof;

FIG. 11 is a right side view thereof;

FIG. 12 is a bottom view thereof;

FIG. 13 is a rear view thereof; and,

FIG. 14 is a left side view thereof.

The broken line portions of the figure drawings are included to show portions of the article that form no part of the claimed design.
